UNITED STATES PATENT OFFICE

JOHN V. PALMER, OF PITTSBURGH, PENNSYLVANIA, ASSIGNOR OF ONE-THIRD TO HARRY I. NEAMAN AND ONE-THIRD TO JAMES M. MAGEE, BOTH OF PITTSBURGH, PENNSYLVANIA

CONNECTER FOR RAILWAY RAILS

Application filed January 30, 1930. Serial No. 424,624.

The general object which I have in view of the abutments bear downwardly on the base flanges of the rails. is the provision of new and improved means for connecting together the adjacent ends of rails.

For this purpose I have invented a connector comprising a pair of fish plates adapted to fit against the opposite webs of the rails and bridging the joint; said fish plates being provided with abutments on their outer faces, a chair extending beneath the rails at the joint and supporting the rail ends from below, said chair having portions extending upwardly at either side of the joint, and wedge blocks driven horizontally between the fish plates and the chair. Bolts extend through registering holes in the rails, the fish plates, the wedge blocks and the chairs.

Wedge pins are preferably driven down between the wedge blocks and the chairs.

Other novel features of construction, and also of arrangement of parts, will appear from the following description.

In the accompanying drawings, wherein I have illustrated a practical embodiment of the principles of my invention, Fig. 1 is a perspective showing a rail joint with my improved connector applied thereto.

Fig. 2 is a section taken along the line 2—2 in Fig. 1.

Fig. 3 is a perspective of one of the wedge blocks.

Fig. 4 is an outer face view of one of the fish plates.

Fig. 5 is an end view of the chair.

Fig. 6 is an elevation of one of the wedge pins.

Referring to the drawings, 1 and 2 represent the two rails whose ends are to be joined. 3 represents the fish plates which bridge the joint and fit against the web of the rails at either side.

Adjacent to their ends the fish plates 3 are provided with one or more bolt holes 4 through which extend the bolts 5 which also engage the usual bolt holes in the rails.

The fish plates are provided intermediate of their ends and on their outer faces with abutments 6 which are horizontally elongated and bridge the joint. The lower faces

7 represents a chair which may be and preferably is a casting having an intermediate or bridge portion 8 which extends transversely of the rails and supports the latter from below adjacent to the joint. 55

The chair 7 is also provided with upwardly extending portions 9 at each side of the rails and also bridging the joint, said portions each being recessed to provide a 60 groove 10 preferably of rectangular cross-sectional shape and an inwardly overhanging shoulder 11.

12 represents a wedge block which is also preferably a casting and which is of the proper cross-sectional shape to be driven lengthwise between the fish plate and its abutment at the inner side and the upwardly extending portion 8 of the chair 7 at the outside and to mate with the surfaces of the 65 same. Thus each of the wedge blocks 12 is provided with a shoulder 13 to mate with the groove 10 of the chair, with a groove 14 to mate with the shoulder 11 of the chair, with a rectangular bottom flange 15 to be interposed between the edge of the rail flanges and the vertical inner wall of the chair, and with an outwardly extending lip 16 which overhangs the top of the chair. 70

The wedge block 12 is preferably slightly 75 tapered towards its entry end and the surfaces which it engages and with which it mates preferably converge slightly, so that when the block 12 is driven longitudinally into place the elements of the connector and the rails will be wedged solidly.

The chair, the wedge blocks and the fish plates are provided with bolt holes 17 which register with each other and with the usual end holes in the rails so that bolts 18 may 80 be inserted and their nuts 19 tightened up to hold the elements rigidly together.

Each of the wedge blocks is provided with a notch 20 in its top lip 16 which is vertically aligned with a vertical groove 21 85 in its shoulder 13. When the wedge block is in place the notch 20 and the groove 21 register with a vertical groove 22 in the shoulder 11 of the chair and with a hole 23 in the bridge 8 of the chair. A bowed, wedge 90

spike 24 of spring steel is driven down into the notch and the registering grooves, thus further tightening the parts together and preventing accidental looseness.

5 It is apparent that my improved connector may be readily and conveniently applied without change in the arrangement or character of the rails or track, and that it will properly and efficiently support and 10 connect the rail ends.

The double wedging action of the parts insures a tight and firm connection.

To remove the connector the spring spikes 15 are withdrawn, the bolts 18 removed and the wedge blocks 12 driven out. The assembly of the connector is likewise simple and convenient.

While for the sake of illustration I have shown my improved connector in connection with rails of the T-type used in steam 20 railway practice, it is apparent that my invention may be likewise used in connection with girder rails and other types and shapes.

25 What I desire to claim is:—

1. A rail connector comprising a pair of fish plates fitting against the webs of the rails at either side and bridging the joint, a chair having a bridge portion extending 30 beneath the rails at the joint to support the rails from beneath and portions extending upwardly at each side, wedge members driven between the fish plates and the chair, and bolts extending through the rails, the 35 fish plates and the chair.

2. A rail connector comprising a pair of fish plates fitting against the webs of the rails at either side and bridging the joint, abutments on the outer faces of the fish 40 plates, a chair having a bridge portion extending beneath the rails at the joint to support the rails from beneath and portions extending upwardly at either side, said upwardly extending portions being 45 provided with horizontal grooves and overhanging shoulders, wedge blocks driven between the fish plates and the upwardly extending portions of the chair and having surfaces arranged to mate with the surfaces 50 of the fish plates and the chair, and clamping bolts extending through holes in the rails and in the fish plates, wedge blocks and chair.

3. A rail connector comprising a pair of 55 fish plates fitting against the webs of the rails at either side and bridging the joint, abutments on the outer faces of the fish plates, a chair having a bridge portion extending beneath the rails at the joint to 60 support the rails from beneath and portions extending upwardly at either side, said upwardly extending portions being provided with a horizontal groove and an overhanging shoulder, wedge blocks driven 65 between the fish plates and the upwardly

extending portions of the chair and having surfaces arranged to mate with the surfaces of the fish plates and the chair, and a bowed spring spike driven between each of the wedge blocks and the chair.

4. A rail connector comprising a pair of fish plates fitting against the webs of the rails at either side and bridging the joint, abutments on the outer faces of the fish plates, a chair having a bridge portion extending beneath the rails at the joint to support the rails from beneath and portions extending upwardly at either side, said upwardly extending portions being provided with a horizontal groove and an overhanging shoulder, wedge blocks driven between the fish plates and the upwardly extending portions of the chair and having surfaces arranged to mate with the surfaces of the fish plates and the chair, a bowed spring spike driven between each of the wedge blocks and the chair, and clamping bolts extending through registering holes in the rails and in the fish plates, wedge blocks and chair.

Signed at Pittsburgh, Pa., this 27th day of January, 1930.

JOHN V. PALMER.
